UNITED STATES PATENT OFFICE.

CHARLES F. HIRT, OF ERIE, PENNSYLVANIA.

ROLLER-SKATE.

SPECIFICATION forming part of Letters Patent No. 329,556, dated November 3, 1885.

Application filed February 12 1885. Serial No. 155,682. (No model.)

To all whom it may concern:

Be it known that I, CHARLES F. HIRT, a citizen of the United States, residing at Erie, in the county of Erie and State of Pennsylvania, have invented certain new and useful Improvements in Roller-Skates; and I do hereby declare the following to be a full, clear, and exact description of the invention, such as will enable others skilled in the art to which it applies to make and use the same.

This invention relates to roller-skates; and it consists in improvements in the means for allowing lateral flexure of the foot-plate.

In most roller-skates in common use lateral flexure is effected by pivoting the trucks to hangers on the under side of the foot-plates, and elasticity of flexure is secured by interposing a spring of rubber. In a few cases metallic springs are used.

For a skate to operate perfectly it should bend in joint easily, so as to require no extra exertion on the part of the skater, and at the same time it should react when the foot is lifted from the floor and bring the wheels into proper line with the foot for the next step or stroke.

The object of my invention is to so construct the joint as to insure a perfect reaction into line with a light and easily-deflected spring,

My device is illustrated in the accompanying drawings, as follows:

Figure 1 is a side elevation of the skate with one of the truck-joints in vertical section. Fig. 2 is a vertical section through the same joint at right angles to the section shown in Fig. 1. Fig. 3 is substantially the same view as Fig. 2, but shows the joint bent or flexed. Figs. 4 and 5 are exaggerated views in perspective of parts of the joint. Fig. 6 is a section view like that in Fig. 1, but shows an alternative construction. Fig. 7 is a rear elevation of the construction shown in Fig. 6.

Letters of reference designate parts, as follows:

A is the foot-plate; B, the hanger-studs on the under side of the foot-plate; C, the joint-sockets on the trucks; C', the journal-sleeve of the axles; D, the axles; E, the wheels; b, the pivot of the point; b', the inclined bearing-faces of the hanger-stud. F is a follower in the joint-socket; f, the inclined bearing-faces of the follower; f', the spring-seat on the

under side of the follower. G is the spring, and H the adjustable or tempering spring-seat.

Such other letters as are used will appear 55 in proper relation herein.

In all the skates of this type of which I am acquainted the spring is depressed on one side as the joint is flexed. I know of no skate having a vertically-guided bearing-piece interposed between the spring and the pivot of the joint—such, for instance, as the follower F, in the construction here shown. This follower is so guided in the socket C that it cannot be tipped; and hence it must bear upon 60 the spring directly or evenly at all points. It is not essential that the part B and the top of the follower F be beveled, as shown, for if they are perfectly flat when they bear upon each other the effect will be the same, substantially; but I prefer the beveled or V shape shown, as it gives the necessary flexure with 70 less depression of spring and the same reactive elasticity.

I have shown a metallic spring, as I prefer 75 its use, as it will retain its elasticity better than rubber, and can be used in my construction equally as well as rubber. The tension of the spring is regulated by the follower H in the bottom of the socket C, which may be adjusted by screwing up into the socket by the screw-thread h, or the lever H' and adjusting-screw H' (seen in Figs. 6 and 7) may be used.

The operation of the joint is clearly shown in Fig. 3. It will be easily seen by observing 85 this figure that it will require very little force to deflect the foot-piece to one side, and that the instant the pressure which deflects it is removed the joint will react instantly, even though the spring be a very weak one, it requiring little more than enough force than is needed to overcome the friction of the follower F on the wall of the socket C. The spring G supports none of the weight of the skater. It is only depressed by the movement of the 90 point of the V on the stud B up the incline face f' of the follower F. This action is the same as regards the force to be exerted, whether the skater throws his foot over to one side more or less, which gives great freedom 100 and ease to the movements of the skater, much more so than where the action of the joint in bending is to pinch a rubber block down on one side or depress a metallic spring sidewise.

While the spring G may be made light and weak, as above stated, I find many prefer it to be strong, and so I make it medium, so it can be adjusted to suit any one by adjusting the 5 lower follower, H.

What I claim as new is—

1. In a roller-skate, the combination, substantially as shown, of the following elements: the stud B, the socket C, the pivot b, the spring 10 G, contained within said socket, and the follower F, interposed between the spring and the stud B and held against lateral tipping on the spring by the walls of the socket C.

2. In a roller-skate, the combination, substantially as shown, of the following elements: the stud B with V-formed end, the socket C, the pivot b, the spring G, contained within the 15 socket, and the follower F, having a V-formed notch to receive the V-formed end of the stud 20 interposed between the spring and the stud and guided against lateral movement by the walls of the socket C.

3. In a roller-skate, the combination, substantially as shown, of the following elements: 25 the stud B and socket C, pivoted together, a

bearing-plate or follower setting against the inner end of the stud B and held against lateral action by the walls of the socket, a spring contained within the socket and acting upon the said bearing-plate, a second follower, H, 30 at the bottom of said socket acting against said spring, and means, substantially as described, for adjusting said follower H to regulate the tension of said spring.

4. In a roller-skate, the combination, substantially as shown, of the following elements: the stud B on the foot-piece, having a V-formed end, the socket C on the truck-frame, the pivot b, the follower F, having a V-formed notch on its upper side to receive the end of the 35 stud, a spring-seat on its lower side, and guided by the walls of the socket against lateral action, the spring G, and the adjustable 40 spring-seat or follower H.

In testimony whereof I affix my signature in 45 presence of two witnesses.

CHARLES F. HIRT.
